UNITED STATES PATENT OFFICE.

GILBERT H. BLAKESLEY, OF BRISTOL, ASSIGNOR TO THE CORBIN CABINET LOCK COMPANY, OF NEW BRITAIN, CONNECTICUT.

TRUNK CATCH OR FASTENER.

SPECIFICATION forming part of Letters Patent No. 325,234, dated September 1, 1885.

Application filed June 9, 1885. (No model.)

To all whom it may concern:

Be it known that I, GILBERT H. BLAKESLEY, of Bristol, in the county of Hartford and State of Connecticut, have invented certain new and useful Improvements in Trunk Catches or Fasteners; and I do hereby declare the following to be a full, clear, and exact description of the invention, such as will enable others skilled in the art to which it appertains to make and use the same.

My invention relates to an improvement in trunk catches or fasteners, the object being to provide a trunk-fastener that shall be composed of few parts, and adapted to be manufactured at a small initial cost and capable of being rigidly fastened against accidental displacement when in use.

With these ends in view my invention consists, essentially, of a trunk-fastener composed of two plates, one plate being provided with a locking tang or projection or recess, and the other provided with a hinged hasp or loop, and with a spring-actuated catch or loop arranged to rigidly secure the hasp or loop against accidental displacement.

In the accompanying drawings, Figure 1 is a plan view of my improved trunk-fastener, showing the parts in their fastened position. Fig. 2 is a similar view illustrating the position of the parts when in their unfastened position. Fig. 3 is a vertical section of the device.

A represents a plate adapted to be fastened to the lid of a trunk, and B a plate to be secured to the body of the trunk, though the parts may be reversed, if desired. Plate A is formed with dowels *a*, which enter sockets *b* in the upper edge of plate B, for the purpose of interlocking the two plates when the lid is fastened to the body, and thus prevent any endwise movement of the trunk-lid on the body, and thereby relieve the trunk-lock and the fastener loops or hasps from undue lateral strains. Plate A is also constructed with a downwardly-projecting tang, C, made rigid or integral therewith, the lower end of the tang having a projection, *c*, formed thereon. Tang C extends downwardly and engages the seat formed between the sockets *b* on plate B.

On plate B is formed a hollow box or projection, D, which may be cast integral with the

plate or struck up from sheet metal, or may be made separate therefrom and secured in place by rivets. On the rear face of the box or projection are cast the lugs *d*, forming a central slot, *e*, within which is placed the stem *e'* of a bolt, E, the beveled end *f* of which projects through a hole, *g*, formed in the upper end of the projection. A spiral spring, F, encircles the stem of the bolt, one end of the spring engaging the lugs *d*, and the opposite end engaging a shoulder, *n*, on the stem of the bolt, whereby the bolt is forced outwardly by the spring. The lower end of the bolt is provided with an arm, *i*, that extends through an elongated slot, *i'*, formed in the upper or outer wall of the box or projection, that portion of the arm that projects through the slot being enlarged and situated within a depressed recess, *j*, so that it may be readily operated by the finger, and yet be protected by the raised walls around the depression within which the projecting arm of the bolt is located. G is a loop or hasp, the cross-bar *k* of which is hinged within a grooved bearing, *l*, formed in the lower end of plate B. The loop is made of a single piece, and may be formed of cast or wrought metal, and is passed over the lower end of the plate and then turned so as to place its cross-bar *k* within the grooved bearing *l*. The free end of the loop is formed with an opening, H, within which is received the projection *c* on the rigid tang C, and is also provided with a cross-bar, *m*, with which engages the spring-actuated bolt or catch. When the fastener is in its unlocked position, the loop is thrown over into the position illustrated in Fig. 2, and when it is desired to effect a fastening the loop is turned upward and over against the beveled end of the bolt, causing the latter to retract and allow the cross-bar to ride over the beveled end of the bolt, when the spring will force the bolt outwardly into the position illustrated in Figs. 1 and 3 and rigidly lock the loop against accidental displacement. This construction of trunk-fastener is strong and durable in its manufacture, occupies but little space, and insures a firm and reliable fastening, and is easily manipulated in fastening or unfastening the lid.

It is evident that many slight changes might be made in the form, relative arrangement,

and in the construction of the different parts of the fastener without departing from the spirit of my invention, and hence I do not limit myself to the particular construction and arrangement of parts shown and described; but,

Having fully described my invention, what I claim as new, and desire to secure by Letters Patent, is—

- 10 1. The combination, with two plates provided with interlocking dowel and sockets, of a hasp or loop hinged to one plate, and a spring-pressed catch or bolt provided with a projection adapting it to be retracted by hand, said catch or bolt being constructed and arranged to detachably secure the free end of the hasp or loop to the hasp-plate, substantially as set forth.

2. The combination, with two plates provided with interlocking dowel and sockets, 20 one plate being provided with a hollow box or projection, of a spring-actuated hand-catch located within said hollow box, and a loop or hasp hinged to the plate provided with the catch or bolt, and adapted to be locked there- 25 to, and also interlock at its free end with the other plate, substantially as set forth.

In testimony whereof I have signed this specification in the presence of two subscribing witnesses.

GILBERT H. BLAKESLEY.
